(57) **CLAIM**

The ornamental design for an electric vehicle, as shown.

DESCRIPTION

FIG. 1 is a front elevational view of an electric vehicle showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a perspective view in the state of use thereof;

FIG. 9 is another perspective view in the state of use thereof; and,

FIG. 10 is a perspective view in alternative state thereof.
